UNITED STATES PATENT OFFICE.

HOLGER V. CLAUSEN, OF NEW YORK, N. Y.

DESIGN FOR A LIQUID-FLASK.

51,136.

Specification for Design. Patented Aug. 14, 1917.

Application filed May 3, 1917. Serial No. 166,271. Term of patent 14 years.

To all whom it may concern:

Be it known that I, HOLGER V. CLAUSEN, a citizen of the Republic of Colombia, South America, and a resident of the city of New York, borough of Manhattan, in the county and State of New York, have invented a new, original, and ornamental Design for a Liquid-Flask, of which the following is a specification.

Reference is to be had to the accompanying drawings in which—

Copies of this patent may be obtained for five cents each, by addressing the "Commissioner of Patents, Washington, D. C."

Figure 1 is a side view of a flask constructed and arranged in accordance with the design;

Fig. 2 is a top end view of the same.

I claim—

The ornamental design for a liquid flask as shown.

HOLGER V. CLAUSEN.
